UNITED STATES PATENT OFFICE.

MATTHEW PRIOR, OF WATERTOWN, ASSIGNOR TO FREDERICK W. MUNROE,
OF SALEM, MASSACHUSETTS.

COIN-OPERATED PLAYING-CARD CASE.

SPECIFICATION forming part of Letters Patent No. 468,827, dated February 16, 1892.

Application filed June 1, 1891. Serial No. 394,634. (No model.)

To all whom it may concern:

Be it known that I, MATTHEW PRIOR, of Watertown, in the county of Middlesex, State of Massachusetts, have invented certain new and useful Improvements in Coin-Operated Playing-Card Cases, of which the following is a description sufficiently full, clear, and exact to enable any person skilled in the art or science to which said invention appertains to make and use the same, reference being had to the accompanying drawings, forming part of this specification, in which—

Figure 1 is a front elevation of my improved card-case; Fig. 2, a vertical section of the same, looking from the rear; Fig. 3, a vertical transverse section; Fig. 4, views similar to that shown in Fig. 2, the card-springs being removed; and Fig. 5, an elevation showing the coin-releasing mechanism.

Like letters and numerals of reference indicate corresponding parts in the different figures of the drawings.

My invention relates especially to a case for holding playing-cards, provided with coin-operated locking mechanism; and it consists in certain novel features, hereinafter fully set forth and claimed, the object being to produce a simple, cheap, and effective device of this character.

The nature and operation of the improvement will be readily understood by all conversant with such matters from the following explanation.

In the drawings, A represents the case, which is preferably rectangular in form, and is provided with a hinged lid b at its top, which is elevated by a pivoted spring d when released from its locking mechanism. The lower portion of the front f is hinged at g, forming a lid h, said lid being fastened to the body by a bolt i, which works in lugs j on the inner face of said lid. A glazed opening k is formed in the lid, through which a card l, containing directions for operating the device, may be exposed. The lid is provided with a lock m, of which the bolt i forms a part, said bolt being pushed by a spring p into its socket 60 (see Fig. 3) in the bottom of the case. In the top of the front f a coin-chute q is formed,

and in said front two marker-openings r are 50 constructed. Disks t, spaced and numbered consecutively on one face, are fitted to rotate in the front f by means of knobs v, said disk being disposed on the inner face of the front f in such manner that their numerals may be 55 consecutively displayed in the openings r. A shutter 15 has an arm 16 secured thereto, which slides in lugs 17 (see Fig. 4) on the inner face of the front, said shutter being adapted to slide vertically between the faces of the 60 disks t and the openings r, and designed to render the counters inoperative without the device is opened for using the cards contained therein.

Two flat springs 18 are secured to a plate 19, which incloses the coin-actuated releasing mechanism on the inner face of the front f. The lower or free ends of said springs are connected by a bar 20. An inner face view of said releasing mechanism is shown in Fig. 70 5. The coin-chute q has its back wall formed by the plate 19, the front f forming the front wall thereof. At the bottom of the main chute q a horizontally-arranged groove 25 is formed, running longitudinally of the plate 19, and in said groove a bar 26 is fitted to slide, the toe 27 of said bar normally projecting into the chute. A V-spring 28 has one end secured to the plate 19, its opposite end bearing against a stud 29 on the bar 26, said spring tending 80 to hold said bar out from the chute. A knob 30 has its spindle passing through a horizontal slot 31 (see Fig. 1) in the front f, said spindle being turned into a socket 32 in said bar. A vertically-inclined boss or projection 33 is 8 formed on the bar 26 and is adapted to engage the edge of the coin C in the chute when said bar is thrown forward, as hereinafter described, and when the bar is drawn back by its spring 28 this projection returns to its normal position. A bell-crank lever 34 is pivoted to the plate 19 below the bar 26, one arm thereof projecting into the chute q in position to receive and support the coin C. The opposite end of said lever has a hook 35, which bears against the guard or stop 36 on the inner face of the plate 19.

A vertically-arranged supplemental chute

37 opens at the lower end into the case-chamber D, of which the lid h forms the door. Said chute has a vertically-inclined mouth 39, (see Fig. 5,) which opens into the main chute 5 q, and at the lower point of which the free end of the horizontal arm of the lever 34 over-laps.

The card-supporter H comprises an angular plate 40, suspended within the case at the rear of the locking mechanism by means of the coiled springs 41, (see Figs. 2 and 3,) secured to the rear wall of the face by one end and having their opposite ends fastened in lugs or arms 42 on said plate. The spring-tensioned bar 20 bears on the front wall 43 of the holder H. A horizontal arm 44 on the bottom of said holder rests on a lug 45 on the shutter-arm 16. The hook 35 of the lever 34 serves as a bolt to enter an eye 46 (indicated 20 by dotted lines in Fig. 5) on the lid to lock said lid.

In the use of my improvement, the cards K being disposed in the holder H, as shown in Fig. 3, and the lids locked, to open the case 25 and obtain the use of the cards a coin is inserted in the chute q, said coin falling upon and being supported by the horizontal arm of the lever 34, as shown by dotted lines C in Fig. 4. The knob 30 is then pushed from 30 right to left, as viewed in Fig. 1, forcing the vertically-inclined projection 33 on the bar 26 against the edge of the coin, driving said coin into the mouth 39 of the supplemental chute 37, as indicated by dotted lines C' in Fig. 5. This depresses the lower arm of the lever 34, drawing its latch end 35 from the eye 46 of the lid b, which is instantly thrown open when 35 thus released by the torsion-spring d. The lid b when closed bears against the top of the cards, forcing the holder H downward slightly and distending the springs 41. As soon as 40 said lid is thrown open, as described, the holder H is drawn upward immediately by the tension of the springs 41, projecting the cards K sufficiently above the top of the case to be readily grasped and removed from the holder. The upward movement of the holder causes its arm 44 to strike a cross-bar 50 on the shutter-arm 16, driving said shutter upward and exposing the numerals on the disk t in the counter-openings r, rendering this mechanism applicable for use in scoring the game. The coin when projected in the supplemental chute 37 falls therefrom into the 55 chamber D. The disposition of the lever 34 determines the size of the coin which may pass into the mouth 39 of said supplemental chute, coins of smaller size dropping therethrough without rendering the mechanism 60 operative. The slide-bar 26 may be moved at will without disturbing the lever 34 until a coin of sufficient size to be forced by its projection 33 against the lower arm of said lever is inserted in the chute q. A guard-plate 55 65 is interposed between the lifting-springs 41 and the cards, said plate being secured at 56

to the case and forming a slide for directing said cards into the holder H. The cards again being disposed in the holder and the lid closed, the parts reassume the position 70 shown in the drawings. The coins may be removed from the chamber D by unlocking the lid h.

The front f is secured to the case by screws passing into the case or in any other desired 75 manner, and the case may be mounted in any suitable position by means of lugs 58 thereon.

Having thus explained my invention, what I claim is—

1. In a coin-operated playing-card case, a 80 case provided with a lid, in combination with a coin-released locking mechanism for said lid, a spring-pushed card-holder adapted to protrude the cards from said case when the lid is released by the unlocking of said mechanism, a hand-operated game-counter, and a shutter operated by the movement of the card-holder to uncover said game-counter, substantially as described.

2. In a coin-operated playing-card case, a 90 case provided with a spring-pushed lid and a main coin-chute, a supplemental chute opening into said main chute, a locking-lever for said lid projecting into said chutes in position to engage the coin, a spring-actuated plunger-slide for forcing said coin against said lever and into said supplemental chute, whereby said lid may be unlocked, and a projection on said slide for returning said lever to operative position when the slide returns, substantially as described. 95

3. In a coin-operated playing-card case, the combination of a case containing a vertically-movable card-holder and provided with a lid, a coin-released locking mechanism for said 100 lid, a hand-operated game-counter, and a shutter normally covering said game-counter and operated by the upward movement of the card-holder to uncover said game-counter, substantially as described. 110

4. In a coin-operated playing-card case, the combination of a case provided with a spring-pushed lid and a main coin-chute, a supplemental chute opening into said main chute, a pivoted bell-crank lever provided at its upper 115 extremity with a latch end which engages and locks the lid when the latter is closed, the lower end of said lever projecting into said main chute in position to engage the coin, a spring-actuated plunger-slide for forcing said 120 coin against the lower end of said lever and into said supplemental chute, whereby said lid is unlocked, and a projection on said slide for returning said lever to operative position when the slide returns, substantially as described. 125

5. In a coin-operated playing-card case, the case and lid, in combination with a coin-released locking mechanism for said lid, a spring-sustained card-holder adapted to protrude the cards from said case when the lid is released, and a counter-shutter operated 130

by the movement of the holder, substantially as described.

6. The case provided with a spring-actuated lid, in combination with coin-released locking mechanism for said lid, a spring-pushed card-holder, the counter mechanism, and a shutter normally covering said counter and actuated

by said holder when the lid is unlocked, substantially as described.

MATTHEW PRIOR.
